KEYPUNCH FOR DOCUMENT CARDS

Wayne L. Aderman, Zumbro Falls, Minn., Douglas C. Antonelli, Raleigh, N.C., and Dennis P. Butterbaugh, James R. Hammer, and Richard J. Ullmer, Rochester, Minn., Edward R. Wiener, Endicott, N.Y., and Frank Wilkey, Jr., Rochester, Minn., assignors to International Business Machines Corporation, Armonk, N.Y., a corporation of New York

Filed July 9, 1969, Ser. No. 18,139

Term of patent 14 years

Int. Cl. D14—02

U.S. Cl. D26—5

FIG. 1

FIG. 2

FIG. 3

FIG. 4

FIG. 5

FIG. 6

FIG. 1 is a perspective view of a keypunch for document cards showing our new design;

FIG. 2 is a top view thereof;

FIG. 3 is a front elevational view thereof;

FIG. 4 is a rear view thereof; and

FIGS. 5 and 6 are end elevational views taken from the opposite ends of the keypunch.

We claim:

The ornamental design for a keypunch for document cards, as shown.
